UNITED STATES PATENT OFFICE.

HERMAN AMES, OF ST. PAUL, MINNESOTA.

CARD OR LABEL HOLDER.

1,113,860.

Specification of Letters Patent.

Patented Oct. 13, 1914.

Application filed June 1, 1912. Serial No. 701,034.

To all whom it may concern:

Be it known that I, HERMAN AMES, a citizen of the United States, residing at St. Paul, in the county of Ramsey and State 5 of Minnesota, have invented new and useful Improvements in Card or Label Holders, of which the following is a specification.

This invention relates to card or label holders especially designed for use upon 10 barrels or other receptacles used in shipping solids or liquids, for holding the shipping label or card bearing the names and addresses of the consignor and consignee.

The object of the invention is to provide 15 a card or label holder especially designed for use on beer kegs, shipping cases, baskets, etc., which is adapted to receive the card or label in such manner as to hold it securely from displacement, so that upon 20 the return of the shipping receptacle from the consignee to the consignor proper credit for its return may be given.

A further object of the invention is to provide a device of this character which is 25 simple of construction, reliable and efficient in use, adapted to be economically manufactured, and which may be used in a ready and convenient manner and without liability of displacement.

30 The invention consists of the features of construction, combination and arrangement of parts hereinafter fully described and claimed, reference being had to the accompanying drawings, in which:

35 Figure 1 is a view showing the application of the invention to a keg or like receptacle. Fig. 2 is a vertical section through the label and keg showing the label retained in position. Figs. 3 and 4 are front 40 and rear views of the device detached. Fig. 5 is a view of a form of label which may be used in connection therewith.

In carrying my invention into practice, I provide a card or label holder 1 comprising 45 a frame shown in the present instance as of elongate rectangular form, cast or stamped or made in any other suitable manner from metal or other desired material. This frame has a main opening 2 for the display of the 50 label and has its top bar provided with a longitudinal slot 3 for the insertion and withdrawal of the label. The lower wall of this slot is formed by an enlarged portion 4 of the bar which projects outwardly beyond 55 the face of the bar and is formed with a beveled rear surface 5 to provide an inclined

chute. The back or rear face of the holder is rabbeted to form a recess 6 of proper size to receive the card or label 7, which is preferably made of paper or other flexible material. This recess extends along the bottom and side bars of the holder outside the main opening 2 and also along the top bar of the holder, the inner wall of the recess terminating flush with the base of the lower 60 offset portion of the top bar. The slot 3 is thus arranged at an angle to the recess, requiring the card to be inserted and withdrawn at an angle and in a flexed condition so as to clear the upper wall of the slot, 65 whereby when the card is fully inserted it will fully contact within the recess and thus be held from displacement.

The side bars of the holder are provided with openings 8 for the passage of suitable 70 fastenings 9 to secure it to the keg or receptacle, and it will be observed that the rear faces of the bars are flush or lie in a common plane so that the holder will bear snugly against the receptacle and hold the 75 label in position without any possibility of loss or displacement. When it is desired to withdraw the label, this may be done by inserting a hooked tool or other device in the label through the opening 2 and bending 80 or flexing the label so that the upper edge thereof will clear the upper wall of the recess and project into the slot, allowing it to be gripped and removed.

Any suitable type of label may be employed, according to the use to which it is to be put, but in Fig. 5 I have shown a form of label which may be adopted in shipping beer or other commodities. As shown, this label is provided with an upper space 10 to 90 receive the name and address of the shipper or consignor, a lower space 11 to receive the name and address of the consignee, and one or more intervening spaces 12 to receive 95 items relative to the character of the shipment or receptacle in which the shipment is made. After the receptacle has been emptied by the consignee, the name of the consignee may be stricken out by running lines therethrough and the name of the consignor 100 allowed to remain as the correction address, or the card may be suitably worded so that both names may be allowed to remain and proper directions given to indicate to the railroad officials or others the destination 105 point. The card will thus serve as a record 110 of the shipment, as well as the return of

the original package, thus enabling the consignor to give proper credit to the consignee for the return of the package or container indicated by the card. By this means a proper record of all shipments and returns may be readily and conveniently kept.

5 I claim:—

As a new and improved article of manufacture, a card or label holder formed of a single piece of material and comprising a body of oblong rectangular form, said body being provided in its front wall with a display opening of corresponding form and being rabbeted on its rear face to provide a recess of greater length and width than said opening, the upper cross bar of the holder

20 having a longitudinal slot corresponding in length with the recess and communicating with the upper portion thereof, the portion of said cross bar below said slot being enlarged and projecting outwardly beyond the face of the bar and having its rear surface beveled downwardly and inwardly to provide an inclined chute, substantially as described.

25 In testimony whereof I affix my signature in presence of two witnesses.

HERMAN AMES.
